UNITED STATES PATENT OFFICE.

SYLVANUS D. LOCKE, OF HOOSICK FALLS, NEW YORK.

HARVESTER.

SPECIFICATION forming part of Letters Patent No. 339,562, dated April 6, 1886.

Application filed January 28, 1886. Serial No. 190,045. (No model.)

To all whom it may concern.

Be it known that I, SYLVANUS D. LOCKE, of Hoosick Falls, in the county of Rensselaer and State of New York, have invented certain new and useful Improvements in Harvesters, 5 of which the following is a specification.

My invention relates mainly to that class of harvesting-machines in which the grain, after being cut or laid upon the platform, is carried 10 sidewise by raking apparatus up over an elevator, as in the well-known Marsh type, and delivered to a binding-table or to an automatic binder, or dropped upon the ground; and for the purpose of properly illustrating 15 the various features I have represented them in connection with a machine of such construction.

The improvement consists in connecting with the draft-tongue one arm of an elbow- 20 lever hinged to the framing of the machine, and to the other arm of said lever a threaded rod passing through a corresponding internally-threaded block or bracket, whereby the machine may be tilted by turning said rod, 25 and in other combinations and details of construction hereinafter described.

In the drawings, Figure 1 is a perspective view of a machine embodying my improvements; and Fig. 2 is an elevation from the 30 stubble-side of the machine with the grain-chute broken away and other parts in section.

The machine consists, primarily, of a platform, A, at the forward edge of which is arranged a sickle bar or cutter, and upon which 35 the grain falls as cut thereby, an elevator-frame, A', rising from the platform to a point above the main drive-wheel, and thence extending down on the opposite side, two supporting-wheels, B and B', the former of which 40 carries the principal weight of the machine and serves as the driving-wheel, from which motion is transmitted to the operating parts of the machine, and the latter being the grain-wheel, and a strong frame supporting the apparatus on the axle of the drive-wheel.

The elevator-frame is braced by diagonal brace-bars *a*, arranged as shown; but this feature I have incorporated in the subject-matter of another application, filed in the 50 Patent Office of the United States on the 11th day of May, 1883, Serial number 94,633, and will not further allude to it herein.

For the purpose of varying the height of cut, the machine is vertically adjustable upon the axle of the main or driving wheel, as is 55 usual in machines of this class, the outer supporting-wheel being likewise adjustable, in order to maintain the platform in a horizontal position.

The mechanism which I prefer to use for 60 raising and lowering the machine is represented in Fig. 2, the axle being furnished with pinions meshing with segmental racks, a lever being provided for rotating the pinions, and suitable detents being employed for 65 holding the pinions against rotation after adjustment, as in Letters Patent granted to me bearing date January 11th, 1881, and numbered 236,503, to which reference is made for a more full description.

In adjusting the machine to any considerable extent upon the driving-wheel its balance is changed somewhat, owing to the segmental outline of the standards in which said wheel is supported, and it is desirable to provide 75 means to compensate for such change, or for establishing a proper balance when wanting from any cause. It is, moreover, desirable to place the seat lower down than has heretofore been customary, and in such position that the 80 driver may see the binding-table, as well as the grain-platform, and that his line of sight may strike the standing grain before the cutters at a very moderate inclination. For this purpose, and in order, also, to permit the various levers and other devices by which the different groups of mechanism are controlled or adjusted to be brought directly and conveniently into the reach of the driver, I mount the seat C upon the rearwardly-projecting beam 90 C', which runs longitudinally beneath the elevator-frame, the standard *c* of said seat being seated in a casting, *c'*, which is adjustable forward and backward upon the beam, and is held at any desired adjustment by means of a bolt, *c''*, 95 passing through the step or casting and through one of a series of holes in the beam. Thus located, the seat is convenient to mount, and the driver seated therein commands a view of the raking-platform and the binding-table on opposite sides of the elevator, and a low-down view of the standing grain, besides being in a convenient position to reach the lever for raising and lowering the machine, the device for

adjusting the tongue, and the levers for varying the position of the reel.

The step or casting c' is formed with an inclined socket to receive the seat-standard, and 5 with a foot-rest, c^2 , to receive the feet of the driver. The standard may be bolted in the socket; but ordinarily its leverage will be sufficient to confine it therein, and for the purpose of staying it when so confined, and to permit 10 its ready removal or adjustment, I provide a rod, c^4 , having its inner end bent to hook into an eye or staple on the frame of the machine, and having a series of perforations at its outer end, to receive a hook or pin on the seat-stand- 15 ard bent at such an angle that after the rod has been applied thereto and hooked into its eye on the frame it cannot be removed without first releasing it from said eye.

As the adjustment of the machine bodily 20 upon the axle tends to change the relation of the draft-tongue to the team, and as it is frequently desirable to change the angle of the cutters to the ground or to raise or to lower them by rocking the harvester upon the carrying-wheels, I have provided means whereby 25 the tongue may be moved positively upon its hinge, thus causing the front of the harvester to sink or to rise, as may be, as the tongue conforms itself to the draft. This tongue D is 30 hinged or jointed to the frame, as usual, and is connected at a suitable distance from said joint by a link, d , with one arm of an elbow-lever, d' , the other arm of which is connected by a ball-and-socket or equivalent joint to the 35 forward end of a rod or shaft, d^2 , which is threaded at its rear end, passes through a similarly-threaded arm or bracket, d^3 , and is provided within reach of the driver's seat with a 40 The rotation of the rod or shaft causes it to

move forward or backward, thereby rocking the elbow-lever upon its pivot, and causing it to elevate or depress the link, and through it the tongue, according to the direction in which the rod or shaft turns.

45

The mechanism relating to the support and adjustment of the seat by itself has been made the subject of an application filed January 28, 1886, Serial No. 190,046, as Division B of the original upon which the present is founded, 50 and I therefore do not lay any claim to it herein; but

What I do claim is—

1. In combination with the draft-tongue hinged or jointed to the framing of the machine, 55 an elbow-lever having one arm connected with the tongue and the other connected with a threaded rod passing through a correspondingly-threaded block or bracket, as and for the purpose set forth.

2. In combination with the hinged tongue, an elbow-lever connected therewith, and a threaded rod connected by a universal joint with the elbow-lever, whereby the rod is permitted both to rotate and to move backward and forward with the lever in adjusting the tongue. 60

3. In combination with the tongue hinged near the front of the elevator, and with the driver's seat located directly in rear of the elevator, an elbow-lever connected with the 70 tongue and a threaded rod passing longitudinally beneath the elevator, and at its front connected with the elbow-lever by a flexible joint and at its rear provided with a crank or hand-wheel within reach of the driver in his 75 seat.

SYLVANUS D. LOCKE.
